CABLE BARRIER SEPARATOR APPARATUS

CROSS-REFERENCE TO RELATED
APPLICATIONS

This application is a continuation of U.S. application Ser. No. 17/301,589, titled "CABLE BARRIER SEPARATOR APPARATUS" filed by Scott Johnson, et al., on Apr. 8, 2021, which is a divisional of and claims the benefit of U.S. application Ser. No. 15/941,564, titled "CABLE BARRIER SEPARATOR APPARATUS," filed by Scott Johnson, et al., on Mar. 30, 2018.

This application incorporates the entire contents of the foregoing application(s) herein by reference.

BACKGROUND OF THE INVENTION

Field of the Invention

The present invention relates to spreading tools and more particularly pertains to a new cable barrier separator apparatus for separating cables from the barrier support so that the barrier support can be replaced.

Description of the Prior Art

The use of spreading tools is known in the prior art. More specifically, spreading tools heretofore devised and utilized are known to consist basically of familiar, expected and obvious structural configurations, notwithstanding the myriad of designs encompassed by the crowded prior art which have been developed for the fulfillment of countless objectives and requirements.

The prior art describes a device interposed between the wire and the ground anchor. The device operates in bending. Another prior art comprises a base portion and an end plate that extends generally vertically from base portion and has an upper edge. One or more are positioned in end plate along upper edge. The cables are secured in slots. Also another prior art includes an anchor-body and terminal post which receive and retain one or more anchor-cables and are anchored to counter balance the force applied to the anchor body by one or more barrier-cables. The system also allows for the release of the anchor-cables during a collision with a vehicle. While these devices fulfill their respective, particular objectives and requirements, the aforementioned patents do not disclose a new cable barrier separator apparatus.

SUMMARY OF THE INVENTION

The general purpose of the present invention, which will be described subsequently in greater detail, is to provide a new cable barrier separator apparatus which has many of the advantages of the spreading tools mentioned heretofore and many novel features that result in a new cable barrier separator apparatus which is not anticipated, rendered obvious, suggested, or even implied by any of the prior art spreading tools, either alone or in any combination thereof. The present invention includes an actuator assembly; and an engagement assembly in communication with the actuator assembly for separating cables from support devices. None of the prior art includes the combination of the elements of the present invention.

There has thus been outlined, rather broadly, the more important features of the cable barrier separator apparatus in order that the detailed description thereof that follows may

2

be better understood, and in order that the present contribution to the art may be better appreciated. There are additional features of the invention that will be described hereinafter and which will form the subject matter of the claims appended hereto.

In this respect, before explaining at least one embodiment of the invention in detail, it is to be understood that the invention is not limited in its application to the details of construction and to the arrangements of the components set forth in the following description or illustrated in the drawings. The invention is capable of other embodiments and of being practiced and carried out in various ways. Also, it is to be understood that the phraseology and terminology employed herein are for the purpose of description and should not be regarded as limiting.

It is an object of the present invention to provide a new cable barrier separator apparatus which has many of the advantages of the spreading tools mentioned heretofore and many novel features that result in a new cable barrier separator apparatus which is not anticipated, rendered obvious, suggested, or even implied by any of the prior art spreading tools, either alone or in any combination thereof.

Still another object of the present invention is to provide a new cable barrier separator apparatus for separating cables from the barrier support so that the barrier support can be replaced.

Still yet another object of the present invention is to provide a new cable barrier separator apparatus that pulls cables away from the barrier support and pushes another cable in the other direction away from the barrier support.

Even still another object of the present invention is to provide a new cable barrier separator apparatus that is handheld and easy to use without the risk of injuring oneself due to the high tension of the cables relative to the barrier support being replaced.

These together with other objects of the invention, along with the various features of novelty which characterize the invention, are pointed out with particularity in the claims annexed to and forming a part of this disclosure. For a better understanding of the invention, its operating advantages and the specific objects attained by its uses, reference should be made to the accompanying drawings and descriptive matter in which there are illustrated preferred embodiments of the invention.

BRIEF DESCRIPTION OF THE DRAWINGS

The invention will be better understood and objects other than those set forth above will become apparent when consideration is given to the following detailed description thereof. Such description makes reference to the annexed drawings wherein:

FIG. 1 is a side perspective view of a new cable barrier separator apparatus according to the present invention.

FIG. 2 is a front exploded perspective view of the present invention.

FIG. 3 is a rear perspective view of the present invention.

DETAILED DESCRIPTION OF THE
INVENTION

With reference now to the drawings, and in particular to FIGS. 1 through 3 thereof, a new cable barrier separator apparatus embodying the principles and concepts of the present invention and generally designated by the reference numeral 10 will be described.

As best illustrated in FIGS. 1 through 3, the cable barrier separator apparatus **10** generally comprises an actuator assembly **11**; and an engagement assembly **20** in communication with the actuator assembly **11** for separating cables from a barrier support **54**. The actuator assembly **11** includes a hydraulic cylinder **12** having a cylindrical barrel **13** and a piston **14** movable relative to the barrel **13** and also includes a control unit **15** conventionally mounted to the hydraulic cylinder **12** for actuating the piston **14**. The control unit **15** includes a control module **16** and a lever **17** conventionally connected to the control module **16** for actuating the hydraulic cylinder **12**. The actuator assembly **11** also includes a hose connector **18** conventionally coupled to the hydraulic cylinder **12** and in communication with the control unit **15** and adapted to be connected to a power source, and also includes a rigid handle member **19** conventionally coupled to the hydraulic cylinder **12** and the control unit **15**.

The engagement assembly **20** includes a support bracket **21** conventionally mounted to the hydraulic cylinder **12** with the barrel **13** conventionally disposed through the support bracket **21** and also includes hook members **28, 33** pivotally mounted to the support bracket **21**. The support bracket **21** includes a wall **22** having opposed longitudinal edges **23, 24** with wings **25, 26** conventionally disposed along the opposed longitudinal edges **23, 24** and perpendicular to the wall **22**. The engagement assembly **20** also includes hook support members **27** spaced apart and disposed through the wings **25, 26**. Each of the hook members **28, 33** has a main portion **29, 34**, a proximate portion **30, 35** terminating in an endless loop **31, 36**, and also has a distal portion **32, 37** longitudinally curved and forming a hook for engaging a respective cable **50**. The hook support members **27** are disposed through the endless loops **31, 36** of the hook members **28, 33** with the hook members **28, 33** being pivotal about the hook support members **27**. The engagement assembly **20** also includes a bracket member **38** conventionally mounted to an end **51** of the piston **14**. The bracket member **38** includes a tubular portion **39** having a closed end **41**, an open end **40** and a bore **42** disposed therein with the piston **14** securely disposed in the bore **42** through the open end **40**, and also includes a cable containment portion **43** conventionally attached at the closed end **41** of the tubular portion **39**. The cable containment portion **43** includes a pair of planar sections **44, 45** angled away from one another and from the tubular portion **39** forming a V-shape with the cable containment portion **43** conventionally coupled to the tubular portion **39** at a junction of the planar sections **44, 45**. The cable containment portion **43** also includes end sections **46, 47** each extending from a distal end **52, 53** of and angled relative to a respective planar section **44, 45** and angled inwardly of the cable containment portion **43** with the end sections **46, 47** being spaced apart and are angled towards one another to ensure that a respective cable **50** is retained by the cable containment portion **43**. The engagement assembly **20** also includes a flexible handle **48** conventionally coupled to the support bracket **21** and further includes an adjustable brace **49** conventionally coupled to the support bracket **21** and to the hydraulic cylinder **12**.

In use, the cable barrier separator apparatus **10** is positioned adjacent to a barrier support **54**. Cables **50** positioned to opposite sides of the barrier support **54** are engaged using the hook members **28, 33** and the bracket member **38**. The hook members **28, 33** are engaged to the cables **50** positioned to one side of the barrier support and the bracket member **38** is engaged to the cable **50** to the opposite side of the barrier support **54**. The hydraulic cylinder **12** is actuated to separate the cables **50** from the barrier support

54. The piston **14** and the bracket member **38** are moved away from the hook members **28, 33** separating the cables **50** from the barrier support **54**.

As to a further discussion of the manner of usage and operation of the present invention, the same should be apparent from the above description. Accordingly, no further discussion relating to the manner of usage and operation will be provided.

With respect to the above description then, it is to be realized that the optimum dimensional relationships for the parts of the invention, to include variations in size, materials, shape, form, function and manner of operation, assembly and use, are deemed readily apparent and obvious to one skilled in the art, and all equivalent relationships to those illustrated in the drawings and described in the specification are intended to be encompassed by the present invention.

Therefore, the foregoing is considered as illustrative only of the principles of the cable barrier separator apparatus. Further, since numerous modifications and changes will readily occur to those skilled in the art, it is not desired to limit the invention to the exact construction and operation shown and described, and accordingly, all suitable modifications and equivalents may be resorted to, falling within the scope of the invention.

We claim:

1. A cable separator apparatus comprising:
an engagement assembly comprising:
a support bracket;
a plurality of cable retaining members, each of the plurality of cable retaining members:
being pivotally mounted to the support bracket at a proximal end,
being configured to extend away from the support bracket in a first plane substantially orthogonal to the support bracket, and,
comprising a cable retaining feature at a distal end;
a bracket member disposed in the first plane between the plurality of cable retaining members, the bracket member:
being configured to be extended, by an actuator, away from the support bracket along a first axis in the first plane, and,
comprising, at a distal end of the bracket member, a cable engagement feature configured to retain a first cable in alignment across the distal end of the bracket member when the cable engagement feature is pressed against the first cable along the first axis of the bracket member during the extension of the bracket member away from the support bracket,

wherein:

the cable engagement feature comprises at least two intersecting surfaces extending away from the distal end of the bracket member, and
the pivotal mounting of each of the plurality of cable retaining members is configured such that the cable retaining feature pivots closer to and further from the bracket member;

and

an actuator system assembly comprising:
a hose connector;
a control unit in communication with the actuator of the engagement assembly;
a power source adapted to be coupled the control unit;
and

a handle coupled to the actuator and support bracket of the engagement assembly and in communication with the control unit.

2. The apparatus of claim 1, wherein each of the plurality of cable retaining members are configured to pivot about corresponding pivot axes oriented substantially parallel to one another. 5

3. The apparatus of claim 1, wherein the support bracket is provided with a wall and at least two wings extending outward from the wall in second and third planes substantially parallel to the first plane. 10

4. The apparatus of claim 3, wherein each of the cable retaining members is pivotally mounted to the support bracket by a corresponding support member passing through the two wings and through at least one aperture in the proximal end of the cable retaining member. 15

5. The apparatus of claim 1, wherein the cable retaining feature comprises a hook pivotally mounted to the support bracket.

6. The apparatus of claim 1, wherein the cable engagement feature comprises a pair of planar sections secured to the bracket member to form a V-shape at the distal end of the bracket member. 20

7. The apparatus of claim 1, wherein the engagement assembly is configured such that, when at least two of the plurality of cable retaining features engage corresponding cables and the cable engagement feature engages the first cable, then operation of the actuator to extend the bracket member along the first axis causes the cable retaining members to operate against the corresponding cables to displace the first cable along the first axis relative to the corresponding cables. 25

8. The apparatus of claim 1, wherein the power source is integral to the control unit.

9. The apparatus of claim 1, wherein the power source is removable. 30

10. A cable separator apparatus comprising:
an engagement assembly comprising:

a support bracket;

a plurality of cable retaining members, each of the plurality of cable retaining members:
being pivotally mounted to the support bracket at a proximal end,

being configured to extend away from the support bracket in a first plane substantially orthogonal to the support bracket, and,

comprising a cable retaining feature at a distal end; and,

a bracket member disposed in the first plane between the plurality of cable retaining members, the bracket member:

being configured to be extended, by an actuator, away from the support bracket along a first axis in the first plane, and,

comprising, at a distal end of the bracket member, a cable engagement feature configured to retain a first cable in alignment across the distal end when the cable engagement feature is pressed against

the first cable along the first axis of the bracket member during the extension of the bracket member away from the support bracket,

wherein the pivotal mounting of each of the plurality of cable retaining members is configured such that the cable retaining feature pivots closer to and further from the bracket member; and

an actuator system assembly comprising:
a hose connector;

a control unit in communication with the actuator of the engagement assembly; and

a power source adapted to be coupled to the control unit. 10

11. The apparatus of claim 10, wherein the actuator system assembly further includes a handle coupled to the actuator of the engagement assembly and the support bracket of the engagement assembly and in communication with the control unit.

12. The apparatus of claim 10, wherein the power source is integral to the control unit. 20

13. The apparatus of claim 10, wherein the power source is removable.

14. The apparatus of claim 10, wherein each of the plurality of cable retaining members are configured to pivot about corresponding pivot axes oriented substantially parallel to one another. 25

15. The apparatus of claim 10, wherein the support bracket is provided with a wall and at least two wings extending outward from the wall in second and third planes substantially parallel to the first plane. 30

16. The apparatus of claim 15, wherein each of the cable retaining members is pivotally mounted to the support bracket by a corresponding support member passing through the two wings and through at least one aperture in the proximal end of the cable retaining member.

17. The apparatus of claim 1, wherein the cable retaining feature comprises a hook pivotally mounted to the support bracket.

18. The apparatus of claim 10, wherein the cable engagement feature comprises a pair of planar sections secured to the bracket member to form a V-shape at the distal end of the bracket member.

19. The apparatus of claim 10, wherein the engagement assembly is configured such that, when at least two of the plurality of cable retaining features engage corresponding cables and the cable engagement feature engages the first cable, then operation of the actuator to extend the bracket member along the first axis causes the cable retaining members to operate against the corresponding cables to displace the first cable along the first axis relative to the corresponding cables.

20. The apparatus of claim 10, the actuator comprising a hydraulic cylinder.

21. The apparatus of claim 20, wherein the hydraulic cylinder comprises a piston coupled to the bracket member such that the bracket member and hydraulic cylinder extend along the first axis.
